(57) **CLAIM**

The ornamental design for a shave ice maker as shown and
described.

DESCRIPTION

FIG. 1 is a top perspective view of a shave ice maker
according to the claimed design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a bottom perspective view thereof.

The even broken lines in the drawings depict unclaimed
portions of the shave ice maker.

The dash-dot-dot broken lines disclose the bounds of the
claimed design; the broken lines form no part of the claimed
design.
